SLIDE OPERATIVE FASTENER STRUCTURE

David Silberman, New York, N. Y., assignor to
Waldes Koh-I-Nerr, Inc., Long Island City,
N. Y., a corporation of New York

Application March 12, 1935, Serial No. 10,607

8 Claims. (Cl. 24—205)

This invention relates to slide fasteners of the type in which two series of cooperating interlocking elements are adapted to be interlocked or disengaged by a manually operated slider 5 movable lengthwise longitudinally of the series of elements.

Slide fasteners of the type in question generally comprise a pair of flexible stringers made of fabric, upon the opposed edges of which are secured the series or rows of interlocking elements. The interlocking elements which are usually made of metal, each have spaced fabric-engaging jaws at the root portions of the elements which are adapted to be clamped against the 10 opposite sides of the stringer to permanently hold the elements upon the stringer. The locking portions of the elements which project outwardly from the opposed edge of each stringer, are provided with complementary surfaces 15 adapted to interlock in interfingered relation with the locking portions of the elements on the other stringer and are swung into and out of such relation by the action of the slider. These conditions require the stringers to be made of a 20 flexible material which is sufficiently strong to afford a reliable and relatively permanent anchoring medium for the elements. The stringers of the indicated type of slide fasteners are usually made in the form of tapes having a thick- 25 ened edge portion upon which the interlocking elements are anchored. These tapes which are usually made from cotton are strong enough to support the elements in a satisfactory manner but possess certain disadvantages which it has 30 become increasingly important to overcome in view of the increased use of slide fasteners in all classes of garments. In the first place, the usual type of stringer tape is substantially heavier and stiffer than the fine flimsy material that 35 is used in women's underwear and clothing. It is not as attractive as the fine fabrics used in such garments and does not take the same dyes as such fabrics so that a perfect color match is not often obtainable. Furthermore, the tape 40 ordinarily used in the stringers is much more expensive than ordinary cloth and must be ordered in large quantities by the slide fastener manufacturer.

The purpose of the present invention is to provide 45 a slide fastener construction of the indicated type which will overcome all the above mentioned and other difficulties and particularly to provide an inexpensive and satisfactory stringer for slide fasteners which will be light 50 and extremely flexible and which will greatly

enhance the beauty and desirability of the slide fastener.

The invention is illustrated in the accompanying drawings in which Fig. 1 is a perspective view of a portion of the stringer before it is 5 folded around the cord and stitched; Fig. 2 is a similar view of the stringer after it has been folded around the cord and stitched; Fig. 3 is an enlarged detailed top view of a portion of the stringer with the interlocking elements attached 10 but uncovered; Fig. 4 is a front end view of the structure shown in Fig. 3; Fig. 5 is a view similar to Fig. 3 showing the covering portion of the stringer in position on the elements; Fig. 6 is a front end view of the structure shown in Fig. 5; 15 Fig. 7 is a top view of a portion of the completed slide fastener; Fig. 8 is a perspective view of a modified form of the stringer before it is folded around the cord and stitched; Fig. 9 is a similar view of the stringer shown in Fig. 8 after it has 20 been folded around the cord and stitched; Fig. 10 is an enlarged detailed top view of a portion of the modified stringer with the interlocking elements attached; Fig. 11 is a front end view 25 of the structure shown in Fig. 10; Fig. 12 is a top view of a portion of the completed slide fastener and Fig. 13 is a sectional view of another embodiment of the invention.

Referring more particularly to Figs. 1 to 7 of the drawings, the reference characters 10 and 30 11 designate generally the opposed stringers of the slide fastener. The stringers are formed of light fine goods such as are ordinarily used in women's clothes or undergarments and may be made of fine cotton cloths such as sateen, mus- 35 lin, long cloth, nainsook, percale, fine linens, silks, rayon, etc. The selection of the particular type of fabric used is determined by the material of the garment with which the slide fastener is to be used and the selected fabric may be 40 colored or decorated to harmonize with the material of such garment. As shown in Figs. 1 and 45 2 of the drawings, each of the stringers are composed of a long strip of the fine goods selected which has first been folded lengthwise so that one edge portion forms the folded or flap portion 12 and then folded lengthwise so that the other edge portion forms the folded or flap portion 13 which overlies the flap portion 12. The flap portion 12 and the central portion 14 50 of the strip are substantially of equal width while the flap portion 13 is approximately three-fifths as wide as the flap portion 12. As is clearly shown in Fig. 1, a cord 15 is positioned longitudinally of such portions adjacent to the 55

free edge of the flap portion 13 so that when the portions are folded as shown in Fig. 2, such edge portion of the flap 13 is folded around the cord 15, (see Figs. 2 and 4). A line of stitching 16 5 may secure the cord 15 in position with relation to the folded portions 12, 13, and 14. I have found that when the strip of fine goods is folded in the manner above described, the resulting thickened edge is sufficiently strong to support 10 in a thoroughly reliable and tenacious manner the interlocking elements. The presence at the thickened edge portion of five layers of the fine goods together with the folded edge portion of the flap 13 provides sufficient fabric material to 15 insure a firm anchorage for the elements. The interlocking elements which comprise a root or anchoring portion 17 and an interlocking portion 18 are anchored upon the thus thickened or strengthened edge of the stringer by clamping 20 the jaws of the root portions of the elements to such edge so that the interlocking portions 18 thereof project outwardly from such thickened edge as is shown in Figs. 3 and 4. By using interlocking elements having the root portions 25 thereof provided with jaws for securely gripping the strengthened edge of the stringer, I have found that it is unnecessary to provide the line of stitching 16 for securing the cord 15 in position with relation to the folded portions of the 30 stringer thereby making the stringer more flexible and maintaining at a minimum the cost of its construction.

The supporting base of the stringer which is designated generally by the reference character 35 19 and which is composed of the flap portions 12 and 13 and the central portion 14 of the strip of material, is adapted to be sewn or otherwise secured to the edge of an opening in a garment.

The folded portion of the stringer which is 40 designated generally by the reference character 20 and which is composed of the flap portion 12 and the central portion 14 of the strip of material, is folded back over the upper jaws of the root portions 17 of the interlocking elements so 45 that the free or outer edge thereof extends over the upper sides of the elements thereby enclosing or covering the root portions of the latter. The width of the folded portion 20 of the stringer is such that it extends out over the upper sides 50 of the interlocking elements a sufficient amount so that when the row of elements is in interlocked position with the row of interlocking elements on the opposed stringer, the free edge thereof abuts the corresponding edge of the opposed 55 stringer to cover or conceal the rows of interlocking elements. The folded portion 20 of the stringer is securely fastened to the upper sides of the elements and to the supporting base 19 of the stringer by means of a line of stitches 60 which may comprise the looped stitches 22 which penetrate the supporting base 19 and the folded portion 20 of the stringer intermediate the interlocking elements on the stringer and stitches 23 intermediate the looped stitches 22 65 which penetrate the layers of the supporting base 19 closely adjacent to the root portions 17 of the elements and longitudinally of the row of elements, these stitches being locked by a bobbin thread in a manner well understood in the art. By reason of this construction the layers of the folded portion 20 are held against the upper sides of the interlocking elements so that puckering of the layers or gaping of the material along the rear edge of the ridge formed by the 70 upper jaws of the root portions of the elements is 75

prevented, thereby producing a neat and strong structure.

The opposed stringers are secured together in the usual manner to form the slide fastener structure. The rows of interlocking elements on the stringers are moved into and out of interlocking engagement by means of a slider 24 which may be of usual and convenient shape and construction, such slider having channels for the reception of the opposed rows of elements and 10 having a pull member 25 which is to be grasped for manually moving the slider 24 longitudinally of the rows of elements.

As the stringers are composed of light fine goods, the slide fastener is light in weight and 15 is extremely flexible, thereby making it particularly adapted for use on women's undergarments or other articles when the flimsiest of materials are used. The appearance of the new structure is attractive and pleasing and the 20 fabric of the stringers can be perfectly matched with the goods of which the garment on which it is to be used is made as the fabric used in the stringer takes the same dyes as the garment material and may even be made from the same 25 piece of goods as the garment. The cost of making a slide fastener according to my invention is less than one-half the cost of the usual slide fastener using the customary cotton tape so that relatively inexpensive garments may now be 30 furnished with a slide fastener structure.

In case it is desired to provide an uncovered slide fastener, the stringers may be arranged in the manner illustrated in Figs. 8 to 11. In that case the strips of fine goods of which the stringers 27 and 28 of the uncovered slide fastener are constituted, are first folded lengthwise so that the edge portions of each strip form the opposed flap portions 29 and 30, as illustrated in Fig. 8. The flap portion 29 is approximately one-half as 40 wide as the central portion 31 of the strip while the flap portion 30 is approximately one-quarter as wide as the portion 31 so that the free edges of such flap portions are separated by a space approximately as wide as the flap portion 30. A 45 cord 32 is positioned longitudinally of the flap portion 29 and adjacently to the free edge thereof so that when the central portion 31 of the strip is folded around the cord 32, the free edge portion of the flap 29 encircles the cord 32 almost completely, as is clearly shown in Fig. 11. A line of stitching 33 may secure the cord 32 in position with relation to the flap 29 and the folded central portion 31. There is thus provided at the resulting thickened edge three layers of the fine 50 goods together with the folded edge portion of the flap 29 which provides sufficient fabric material to insure a firm anchorage for the clamping jaws 34 of the elements 35. In this construction the supporting base of the stringer is composed 55 of two sections between which the fabric of the garment is to be secured, the upper section being composed of the flap 30 and a part of the central portion 31, and the lower section being composed of the flap 29 and a part of the central 60 portion 31, as shown in Fig. 11. A line of stitching 36 which extends longitudinally of the stringer and which is positioned in back of the anchoring portions of the interlocking elements, penetrates the three layers of fabric at this 65 point thereby preventing puckering of the fabric layers after the stringers are secured to the garment.

Fig. 13 illustrates a modified form of a covered slide fastener in which the fabric is first ar- 70 75

5 ranged in a manner similar to that shown in Fig. 8 except that the right end portion of the strip, as viewed in Fig. 8, is folded to form a flap portion 37 which is wider than the flap portion 30 of the stringer illustrated in Fig. 8. Thus when the central portion 31 is folded around the cord 32, a covering flap consisting of the flap portion 31 and that part of the central portion 31 which the former overlies is provided which is 10 shorter in width than the supporting section which comprises the flap 28 and the remaining part of the central portion 31. As is shown in Fig. 13, the covering flap is folded around the anchoring portions of the interlocking elements, 15 thereby covering such elements. The covering flap is secured to the upper sides of the interlocking elements by means of a line of stitches which may comprise the looped stitches 22, 20 stitches 23, and a bobbin thread as hereinbefore described.

It will be understood that various other modifications may be resorted to within the spirit of the invention without departing from the scope of the claims.

25 I claim:

1. A fastener structure of the slide operated type comprising a pair of stringers, each of said stringers being composed of a strip of thin fine goods folded along its length so that the edge 30 portions thereof form flaps which overlap the central portion of the strip, said central portion and at least one of said flaps being folded along their lengths to form a folded edge, a strengthening element extending longitudinally of said 35 stringer and positioned intermediate the folded parts of said central portion and adjacent to said folded edge, and a row of interlocking elements having attaching portions for securing them to the folded edge of said stringer, the attaching 40 portions thereof being in the form of jaws clinched around said folded edge and said strengthening element.

2. A fastener structure of the slide operated type comprising a pair of stringers, each of said stringers being composed of a strip of thin fine goods folded along its length so that the edge 45 portions thereof form flaps which overlap the central portion of the strip, said central portion and the free end portion of one of said flaps being folded along their lengths to form a folded edge, a strengthening element extending longitudinally of said stringer and positioned in between the fold formed on the free end portion of said flap, and a row of interlocking elements 50 having attaching portions for securing them to the folded edge of said stringer, the attaching portions thereof being in the form of jaws clinched around said folded edge and said strengthening element.

60 3. A fastener structure of the slide operated type comprising a pair of stringers, each of said stringers being composed of a strip of thin fine goods folded along its length so that the edge portions thereof form flaps which overlap the 65 central portion of the strip, at least one of said flaps being at least as wide as the width of the stringer in its finished form, said central portion of the strip being folded along its length about the free edge of one of said flaps to form a folded edge having at least three layers of the 70 fine goods, a strengthening element extending longitudinally of said stringer and positioned in between the fold forming said folded edge, a line of stitching extending longitudinally of said 75 stringer and securing said strengthening ele-

ment in position between the fold forming said folded edge, and a row of interlocking elements having attaching portions for securing them to the folded edge of said stringer, the attaching portions thereof being in the form of jaws clinched around said folded edge and said strengthening element.

4. A fastener structure of the slide operated type comprising a pair of stringers, each of said stringers being composed of a strip of thin fine goods folded along its length so that the edge portions thereof form flaps which overlie the central portion of the strip, at least one of said flaps being at least as wide as the width of the stringer in its finished form, said central portion being folded along its length about the free edge of one of said flaps to form at least three layers having a width equal to the width of the stringer in its finished form, a strengthening element extending longitudinally of said 10 stringer and positioned in said last-mentioned fold upon the edge portion of the flap about which said fold was made and adjacent to the folded edge formed by such fold, a row of interlocking elements having attaching portions 15 for securing them to said folded edge, the attaching portions thereof being in the form of jaws clinched around said folded edge and said strengthening element and a line of stitching extending longitudinally of said stringer and positioned intermediate the row of interlocking elements and the edge portion of the stringer which is to be secured to the edge of an opening in an article, said line of stitches penetrating 20 all the layers of the stringer and securing them 25 together.

5. A fastener structure of the slide operated type comprising a pair of stringers, each of said stringers being composed of a strip of thin fine goods folded upon itself to form a plurality 30 of layers of the fine goods, said folded strip being again folded on itself to form a pair of flaps of unequal width, the folded edge formed by said flaps having at least three layers of the fine goods, a strengthening element extending longitudinally of said stringer and positioned in between the fold formed by said flaps and adjacent the folded edge thereof, a row of interlocking elements having attaching portions 35 for securing them to the folded edge of said stringer, the attaching portions thereof being in the form of jaws clinched around said folded edge and said strengthening element, one of said flaps being adapted for attachment to the edge of an opening in an article, and the other 40 of said flaps being reversely folded over the attaching portions of said elements so as to extend toward the interlocking portions thereof, and stitches securing said reversely folded portion 45 of the second mentioned flap to the covered sides of the interlocking elements.

6. A fastener structure of the slide operated type comprising a pair of stringers, each of said stringers being composed of a strip of thin fine goods folded along its length so that the edge 65 portions thereof overlap the central portion of the strip, said folded strip being again folded on itself along a line extending lengthwise of the stringer and adjacent to the free edge of one of the folded portions so that the free edge 70 portion of said folded portion is folded on itself and a pair of flaps of unequal width are formed, the folded edge formed by said flaps having at least three layers of the fine goods, a strengthening element extending longitudinally 75

of said stringer and positioned in between the fold formed on the free end portion of said folded portion, a row of interlocking elements having attaching portions for securing them to the folded edge of said stringer, the attaching portions thereof being in the form of jaws clinched around said folded edge and said strengthening element.

5. the folded edge of said stringer, the attaching portions thereof being in the form of jaws clinched around said folded edge and said strengthening element, the wider of said flaps being adapted for attachment to the edge of 10 an opening in an article, and the other of said flaps being reversely folded over the attaching portions of said elements so as to extend toward the interlocking portions thereof, and stitches 15 securing said reversely folded portion of the second mentioned flap to the covered sides of the interlocking element.

7. A fastener structure of the slide operated type comprising a pair of stringers, each of said stringers being composed of a strip of fine 20 goods folded on itself to form at least two layers of the fine goods having a width at least as wide as the width of the stringer in its finished form, said folded strip being again folded on itself to form a folded edge having at least 25 three layers of the fine goods, a strengthening element extending longitudinally of said stringer and positioned in between the two first-mentioned layers and the flap formed by said last-mentioned fold and adjacent to the folded edge 30 formed by such fold, and a row of interlocking elements having attaching portions for securing

them to the folded edge of said stringer, the attaching portions thereof being in the form of jaws clinched around said folded edge and said strengthening element.

8. A fastener structure of the side operated type comprising a pair of stringers, each of said stringers being composed of a single strip of fabric folded upon itself to form a pair of flaps of unequal width and provided with a folded edge having sufficient fabric material to insure 10 a firm anchorage for the interlocking elements, a strengthening element extending longitudinally of said stringer and positioned in between the fold forming said folded edge in unattached relation thereto, and a row of interlocking elements having attaching portions for securing them to the folded edge of said stringer, the attaching portions thereof being in the form of jaws clinched around said folded edge 15 and said strengthening element and securely holding the same together, one of said flaps being adapted for attachment to the edge of an opening in an article, and the other of said flaps being reversely folded over the attaching portions of said elements so as to extend toward 20 the interlocking portions thereof, and stitches securing said reversely folded portion of the second-mentioned flap to the covered sides of 25 the interlocking elements.

30

DAVID SILBERMAN.
